CLAIM

The ornamental design for an electric iron, as shown and described.

DESCRIPTION

FIG. 1 is a rear and top perspective view of an electric iron design showing our new design.

FIG. 2 is a front and bottom perspective view of an electric iron.

FIG. 3 is a front view of an electric iron.

FIG. 4 is a rear view of an electric iron.

FIG. 5 is a left side view of an electric iron.

FIG. 6 is a right side view of an electric iron.

FIG. 7 is a top view of an electric iron; and,

FIG. 8 is a bottom view of an electric iron.

Any shading is not features of the design but are utilized to illustrate the surface contours of the electric iron design in the drawings.

1 Claim, 8 Drawing Sheets
